Primary Examiner — Karen E Eldridge Powers*(74) Attorney, Agent, or Firm* — Fellers, Snider, Blackenship, Bailey & Tippens, P.C.(57) **CLAIM**

The ornamental design for a cap, as shown and described.

DESCRIPTION

FIG. 1 is a front perspective view of the cap showing my design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is a rear perspective view thereof.

The six rows of broken lines on the bill of the cap are lines of stitching that form no part of the claimed design.

The size adjustment strap shown in broken lines on the back portion of the cap forms no part of the claimed design.
